UNITED STATES PATENT OFFICE.

SAMUEL COHN, OF NEW YORK, N. Y.

DESIGN FOR A LABEL-BLANK.

40,530.

Specification for Design.

Patented Feb. 22, 1910.

Application filed December 23, 1909. Serial No. 534,740. Term of patent 7 years.

To all whom it may concern:

Be it known that I, SAMUEL COHN, a citizen of the United States, residing at the city of New York, borough of Manhattan, in the county and State of New York, have invented a new, original, and ornamental Design for Label-Blanks, of which the following is a specification, reference being had to the accompanying drawing, forming part thereof, in which is shown a face view of a label-blank incorporating my said design.

In said drawing the label blank is shown as of rectangular outline having a plain border. In the central portion of said label blank, adjacent to its upper edge, is arranged an ornament, of irregular trapezoidal outline, upon which is displayed an

elliptical shield bearing three stars. Said shield is shown surmounted by a crown and is supported by two lions issuant. Sprays of grain extend from the center of the lower edge of said ornament, pass under said ornament, and project at either side thereof.

Below the central portion of the label blank is longitudinally arranged an ornamental band, bisymmetrically inclosed by conventionalized foliage.

I claim—

The ornamental design for a label blank, as herein shown and described.

SAMUEL COHN.
